UNITED STATES PATENT OFFICE.

ORANGE O. OZIAS, OF DAYTON, OHIO, ASSIGNOR TO THE COMPUTING SCALE COMPANY, OF OHIO.

DESIGN FOR A BASE MEMBER FOR SCALES.

SPECIFICATION forming part of Design No. 31,924, dated December 5, 1899.

Application filed October 30, 1899. Serial No. 735,328. Term of patent 7 years.

To all whom it may concern:

Be it known that I, ORANGE O. OZIAS, a citizen of the United States, residing in Dayton, in the county of Montgomery and State of Ohio, have produced a new and original Design for a Base Member for Scales, of which the following is a specification, reference being had to the accompanying drawings, forming part thereof, in which like numerals refer to like parts.

In the drawings, Figure 1 represents a plan view of a base member for a scale embodying my invention and design. Fig. 2 is an exterior side elevation view thereof, and Fig. 3 is a sectional elevation view thereof on line X X of Fig. 1.

The leading or essential feature of my design consists of a rectangular member having upwardly-extending sides sloping inwardly toward its top, a rectangular opening through the top and near one side thereof, vertical flanges at the bottom of said member, a cross member across the top of said vertical flanges

and the bottom of said member, and a projection on the outer edge of one of said vertical flanges.

In said drawings, 10 represents said rectangular member having upwardly-extending sides sloping inwardly toward its top. 11 represents said rectangular opening through the top and near one side thereof. 12 represents said vertical flanges at the bottom of said member. 14 represents said cross member across the top of said edge of said vertical flanges and the bottom of said member. 15 represents said projection on the outer edge of one of said vertical flanges 12.

What I claim is—

The design for a base member for a scale, substantially as shown and described. 46

In witness whereof I have hereunto set my hand this 30th day of September, 1899.

ORANGE O. OZIAS.

Witnesses:

CHARLES W. JAMES,
